(57) **CLAIM**

The ornamental design for a display screen with an animated graphical user interface for medical software, as shown and described.

DESCRIPTION

FIG. 1 is a first image of a display screen with an animated graphical user interface for medical software showing the new design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is an eighth image thereof;

FIG. 9 is a ninth image thereof;

FIG. 10 is a tenth image thereof;

FIG. 11 is an eleventh image thereof;

FIG. 12 is a twelfth image thereof;

FIG. 13 is a thirteenth image thereof;

FIG. 14 is a fourteenth image thereof;

FIG. 15 is a fifteenth image thereof; and,

FIG. 16 is a sixteenth image thereof.

The broken lines showing the display screen form no part of the claimed design. The broken lines showing text and other graphic elements form no part of the claimed design.

The appearance of the image transitions sequentially between the images shown in FIGS. 1-16. The process or period in which one image transitions to another forms no part of the claimed design.
